UNITED STATES PATENT OFFICE.

JOHN F. REYNOLDS, OF PASADENA, AND ALBERT P. WORTHINGTON, OF LOS ANGELES,
CALIFORNIA.

TOY.

Application filed January 19, 1921. Serial No. 438,296.

To all whom it may concern:

Be it known that we, JOHN F. REYNOLDS, residing at Pasadena, in the county of Los Angeles, State of California, and ALBERT P. 5 WORTHINGTON, residing at Los Angeles, in the county of Los Angeles and State of California, both citizens of the United States, have invented certain new and useful Improvements in Toys, of which the following 10 is a specification.

Our invention relates to toys and particularly to an improved form of rolling toy. Our invention comprises a hoop which may be rolled along the sidewalk or other surface, a rotative device being mounted within the hoop and adapted to be rotated in a direction at right angles to that of the hoop while the latter is in motion. In the preferred form of our improved device the hoop 15 carries a transverse frame extending on opposite sides of the same in which is rotatably mounted a shaft which extends axially of the hoop. A pin extends forwardly from this shaft and on this pin is rotatably mounted 20 a form of windmill or whirligig device. Extending rearwardly from the shaft is a curved blade which acts as a counter balance for the windmill device. When the hoop is 25 rolled in a forward direction the air pressure on the rearwardly extending curved blade serves to maintain the windmill device in approximately a vertical plane at right angles to the direction of movement of the hoop. The windmill device is provided with 30 radially extending blades which are angularly disposed in the nature of propeller blades so that the pressure of the air on the same, as the hoop is rolling, will cause 35 the device to rotate about its own axis.

40 In order that a clearer understanding of our invention may be had attention is hereby directed to the accompanying drawings forming part of this application and illustrating one form of our invention. In the 45 drawings Fig. 1 represents a perspective view of the improved toy, Fig. 2 is a section taken on line 2—2 of Fig. 3 and Fig. 3 is a rear elevation of the toy, partly shown in section.

50 Referring to the drawings the device comprises a hoop 1 which is suitably formed of wood and is of desired size. A transverse frame is provided, this preferably consisting of a pair of metal bands 2, 2 which are 55 curved so as to extend outwardly in approxi-

mately semi-cylindrical form on each side of the hoop, the ends of the bands 2, 2 being secured to opposite faces of hoop 1, by screws or other suitable securing devices, as is shown at 3.

60 A shaft 4 extends transversely of the hoop and is rotatably mounted in the frame 2, 2. Preferably this shaft is mounted in the axis of the hoop and is suitably supported by means of pins 5, 5 which extend inwardly 65 through the metal frame members 2, 2, into suitable openings which are formed axially in the end portions of shaft 4.

70 The windmill or whirligig device 6 is rotatably mounted on a pin 7 which extends forwardly from shaft 4. The curved counter balance blade 8 extends rearwardly from shaft 4. Preferably blade 8 is secured in position by providing the same with a 75 forwardly extending tongue 9 which is bent up in an inverted U-shape at the forward side of shaft 4 and is bent around the under side of the shaft, the pin 7 extending entirely through shaft 4 so that it will pierce two thicknesses of tongue 9 at the front side 80 of shaft 4 and one thickness of the same at the rear shaft 4 as is indicated in Fig. 2.

85 Preferably the windmill device 6 is provided with a rearwardly extending loop or bail 10 through which pin 7 extends. The windmill device 6 has a central body portion 11 from which the blades 12 extend, this central portion 11 being substantially flat. The pin 7 extends through portion 11 of the 90 rotative device as well as the loop 10, the head of the pin being in front of the portion 11 of the device, the latter having accordingly a two-point bearing on the pin.

95 The device 6 is suitably formed of thin sheet metal with the arms or blades 12 extending radially. The blades 12 are bent or curved like propeller blades, the blades, therefore, having forward lateral edges 13 from which the blades slant rearwardly, to their rear lateral edges. Accordingly, sufficient 100 pressure of air against the front of the device 6 will cause the same to rotate about its axis.

105 The hoop may be rolled in any suitable way as by the aid of a short stick or the hand applied to the outer edge of the hoop. When the hoop is rolled forwardly, that is towards the left, referring to Fig. 2, the air pressure against the curved counter balance blade 8 will serve to maintain the windmill 110

devices 6 in an approximately vertical position at right angles to the direction of motion of the hoop. Air pressure will be developed against the front surfaces of the 5 blades 12 by the motion of the hoop and this will cause rotation of the device 6 about pin 7 as an axis whenever the hoop is rolled with sufficient rapidity.

It will be noted that the frame 2 provides 10 a guard to prevent injury of the windmill device and the counter balance 8. When the hoop falls over it will rest partly on the edge of the hoop and partly on the undermost portion of frame 2, in which case 15 neither the blade 8 nor any of the blades 12 will touch the pavement.

It will be understood that our invention is not limited strictly to the details of construction described but is as broad as is indicated by the accompanying claims.

What we claim is:

1. In a toy, in combination, a hoop, a device mounted within said hoop for rotation with respect thereto, and means, including 25 an air blade associated with said device, for maintaining said device in a substantially constant inclination with respect to a surface over which said hoop is rolled.
2. In a toy, in combination, a hoop, a device 30 mounted within said hoop for rotation with respect thereto, and means, including an air blade associated with said device, for maintaining said device in a substantially constant inclination with respect to a surface over which said hoop is rolled, said device including a blade wheel rotatable with respect to said air blade.

3. In a toy, the combination of a hoop, a transverse frame secured thereto, a shaft extending axially of said hoop and rotatably supported by said frame, a pin extending from said shaft, a device adapted to be rotated by the air rotatably mounted on said pin, and means for maintaining said device in an approximately vertical plane when said 45 hoop is rolled over a surface.

4. In a toy, the combination of a hoop, a transverse frame secured thereto, a shaft extending axially of said hoop and rotatably supported by said frame, a pin extending 50 forwardly from said shaft, a device adapted to be rotated by the air rotatably mounted on said pin, and a curved counter balance blade extending rearwardly from said shaft.

5. In a toy, the combination with a hoop, 55 two curved frame members secured to said hoop and extending outwardly on opposite sides thereof, a shaft extending transversely of said hoop, having its ends journalled in said frame members, a pin projecting from 60 said shaft, a device mounted on said pin for rotation with said shaft, and means, including an air blade connected with said device, for maintaining said device in a substantially constant inclination with respect to a 65 surface over which said hoop is rolled.

This specification signed and witnessed this 12th day of January, 1921.

JOHN F. REYNOLDS.
ALBERT P. WORTHINGTON.
